UNITED STATES PATENT OFFICE.

ELMO M. DAUGHERTY, OF WEBB CITY, MISSOURI.

ORE JIG.

Application filed March 4, 1924. Serial No. 696,857.

To all whom it may concern:

Be it known that I, ELMO M. DAUGHERTY, a citizen of the United States, residing at Webb City, in the county of Jasper, State of Missouri, have invented certain new and useful Improvements in Ore Jigs, of which the following is a specification.

This invention relates to improvements in ore jigs.

10 In the jigging process of mineral concentration it is often necessary to separate the ores of two or more different metals into several grades or qualities of sieve and hutch concentrates before the final separation 15 of the different ores from each other and from their associated gangue matters; and it has been found that such work cannot for several reasons be performed to the best economic advantage by using a plurality of 20 single compartment jigs of wholly separate and independent construction.

Where a large number of preliminary separations of ores of different sizes and gravities is desired, the use of single compartment 25 jigs requires the use or employment of an additional and unnecessary number of drive belts, pulleys, drive shafts, journal boxes, elevators, etc., which increase the cost of installation and maintenance.

30 In the usual construction and operation of jigs of the tandem type, it is highly essential in the treatment of many ores that such sieves be somewhat inclined toward the head end of the jig for the purpose of effecting 35 a balance between the transporting effects of overflow waters and the attraction of gravity, thereby preventing the ore-beds from drifting toward the discharge end of the sieves and insuring a better distribution 40 of such beds over the surfaces of the screens. Furthermore, in the construction of jigs of this type the ore-feed is received only at one end of the sieves and the overflow products are discharged only at the opposite ends and 45 it is essential that the flow-lines have a very considerable degree of decline toward the places of discharge, for the purpose of accelerating the velocity of overflow waters and enabling the treatment of a sufficient tonnage of mineral. Thus the sieves of tandem type jigs are inclined toward the feed 50 ends, while the flow-lines are inclined toward

the discharge ends of the jigs, causing the beds of material to form an unequal or irregular thickness, thereby causing unequal 55 and restricted settling conditions.

As a result of the conditions above mentioned, the pulsating or rising currents of water from beneath the sieves will seek an outlet in the place of least resistance, this 60 place being near the discharge ends of the sieves where the mineral beds are thinnest and irrespective of the adjustment of the water agitating means, it is impossible to prevent too much activity on the discharge 65 ends of the mineral beds or insufficient activity on the head ends. As a result, low gravity minerals and middling products do not encounter sufficiently free settling conditions on the head ends of the sieves and 70 on nearing the discharge ends where the rising current of water is stronger, a very considerable portion of such minerals are forced onto the next succeeding sieve below and so on throughout the entire length of 75 the jig and finally lost in the tailing discharges.

In the operation of a jig of the tandem type, it is imperative that a greater quantity of water be admitted below the sieve 80 of each compartment than is being emitted at the sieve discharge faucets below, and as the overflow of water passes onto the next succeeding sieve below it, the volume and velocity of such overflow waters increases 85 throughout the entire length of the jig, causing:

First: The loss of considerable quantities of fine ores carried off in suspension with overflow waters,

Second: The loss of coarser material and middling products of low gravities which are carried off with overflow products as a result of a too high velocity of overflow 95 waters and minerals and unnecessary agitation of the surfaces of mineral beds and its resultant hinderance of the stratification of minerals of low specific gravities.

As previously stated in the operation of multiple compartment jigs of the tandem 100 type, the volume and velocity of overflow waters increases on passing each succeeding sieve compartment and which effects, as a general result, a decreasing efficiency of the

several sieve compartments throughout the length of such jigs.

By the law of gravity the first and most efficient sieve compartments of these tandem type jigs must be used in concentrating the minerals of the higher specific gravities, and which are the most easily concentrated, while the last and least efficient sieves are employed in extracting the lower gravity minerals and middling products which are the most difficult of extraction and very considerable quantities of valuable minerals are lost as a result of treating the most refractory minerals contained in the feed, on the least efficient compartments of such jigs.

It is further noted that jigs now employed in a typical lead and zinc mill have usually from five to seven sieve compartments, several of which are often employed in extracting the same kind or quality of mineral products, and such coarse minerals and middling products which do not settle down low enough in their progress along the first sieves, to be removed at the sieve ore or middling gates, must flow upward and pass over the discharge end of said sieves where it again becomes mixed with minerals of lower gravities, and as these minerals pass onto the next succeeding sieve below, a higher velocity of overflow water is encountered and as a natural consequence, such minerals are transported the length of the second sieve in less time than was required for such minerals to pass over the preceding sieve. Thus the chances of recovering these lower gravity minerals by means of such jigs, become less on passing each successive compartment; a considerable portion of valuable minerals being lost as a result of these sieves being of insufficient lengths and too great in number.

Also it is to be here noted that most jigs now in use are so constructed that it is necessary to draw the sieve concentrates at right angles with respect to the direction of the ore feed and flow, and it is obvious that low-gravity minerals and middling products will not move as readily on a line diagonal with the direction of flow as if such gates opened in a direct line with the flow, and valuable ore and minerals are often lost in tailing dischargings as a result of such conditions.

Furthermore, the jig ore and middling gates now in use are so constructed that the opening and closing of the same is effected only by the jig operator and remain stationary during the operation of the jig except when adjusted by the operator. Now, as the beds of minerals move upward and downward by force of the vertically reciprocating action of the jig plungers, it is obvious that stratas of minerals of widely varying sizes and gravities move up and down past such stationary gate openings and permit

fine low gravity minerals and gangue matters to escape carrying therewith much coarser and higher gravity ores, and this is especially objectionable in removing low gravity minerals and low gravity products by means of such gates. Various types of gates have been devised to overcome this deficiency and usually all require the drawing of the sieve concentrates at right angles with the direction of flow or have only a single outlet and interfere somewhat with the work of cleaning the screens or obstruct the escape of overflow products over the discharge end of the sieve.

Furthermore, it should be here noted that owing to the unequal thickness of the mineral beds on jigs of the types heretofore referred to, settling conditions are considerably restricted near the feed ends of the sieves and which causes clogging or binding of the interstices of the screen. This clogging of the screens has a strong tendency toward reducing both the capacity and efficiency of jiggling operations and necessitates the cleaning of screens as frequently as once every hour during operation of the jig.

With that heretofore recited in view, it is an object of the present invention to provide an ore jig which is capable of operating in a highly efficient manner through provision of means for enabling more uniform thickness in ore beds, by providing means to cause the velocity of overflow waters and minerals to decrease between the places of feed entry and overflow; by providing longer sieves; by providing more efficient ore and middling gates, and by providing means for increasing or diminishing the action of the ore beds during the operation of the jig.

Other objects, and objects relating to details of construction, combination and arrangement of parts will hereinafter appear in the detailed description to follow.

The invention is illustrated by way of example in the accompanying drawings, in which:

Figure 1 is a view in side elevation of a form of jig embodying the present invention,

Figure 2 is a top plan view of the same,

Figure 3 is a central longitudinal section of the jig shown in Figures 1 and 2 and with parts broken away and shown in section in order to clearly illustrate the operation of the jig,

Figure 4 is a vertical transverse sectional view through the middle compartment of the jig,

Figure 5 is a partial vertical sectional view illustrating the construction and arrangement of middling gate of the present invention,

Figure 6 is a detail view in side elevation showing the co-operative parts of the middling gate,

Figure 7 is a detail view partly in side

elevation and partly in section further illustrating the manner in which the form of middling gate employed operates.

Figure 8 is a view similar to Figure 1 but showing a modified form of jig, and

Figure 9 is a top plan view of the same.

Like reference numerals designate corresponding parts throughout the several views.

Referring to the drawings in detail, and particularly Figures 1 to 7, inclusive, the jig shown comprises a suitable structure whereby to provide three different tanks A, B and C, respectively, and each tank comprises a rear wall 10, a front wall 11, two end walls 12 and bottom 12'. Each tank A, B and C is provided with a vertical and transverse division wall 13, the forward and upper end portion of which is offset, as at 14, and thereby to provide a support for the longitudinally extending division wall 15, said division wall together with the transverse division walls 13 forming in each tank A, B and C a pair of plunger compartments 16 which occur at the rear of the division wall 15 and a pair of hutch compartments 17 which occur forward to the division wall 15 and which communicate with the plunger compartments, as illustrated to advantage in Figure 4. Each compartment 17 and associated compartment 16 is provided with a false bottom 18 which is inclined, as shown and which extends between the rear wall 10 and front wall 11 of each tank. The false bottom 18 may be supported by a brace 19, and each compartment 17 may be provided with an outlet 20 which may be controlled through the means of a faucet or the like, not shown.

The rear side wall 10 may extend above the front walls 11 as shown to advantage in Figure 4 and also the end walls 12 and partition walls 13 may be extended upwardly so that the same are of a height equal to the rear wall 10. These walls are utilized for supporting the shaft 22, said shaft carrying a suitable pulley 23, whereby the same may be rotated. The shaft is suitably journaled and has operatively connected thereto a plurality of connecting rods 24, one for each of the plunger compartments 16. Each connecting rod 24 carries at its lower end an inverted U-shaped frame member 25, the terminals of which support a plate 26. A second plate 27 is provided and between the plates 26 and 27 there is clamped a plunger 28, said plunger being squared and conforming to the shape of a plunger compartment 16.

Each connecting rod is connected to the shaft 22 by the means of a second casting 34 and within this casting there is disposed an eccentric 35 which is secured to the shaft 22 and thereby with the turning of the shaft the plungers are reciprocated within the

plunger compartments 16. The eccentric members 35 are so arranged that the plungers will operate for agitating the water within the plunger compartments at different intervals in order to obtain a uniform 70 operation of the device. It is also necessary to secure the eccentricities of each of the companion compartments 16 so that they operate together or simultaneously and to arrange the eccentricities of different compartments 120° apart with respect to the circumference of the shaft and thus affecting a balance between the plungers of the different compartments. 75

In each of the tanks A, B and C there is 80 mounted a sieve 38. The sieve of the middle tank B is arranged at a higher elevation than the sieves of the end tanks as illustrated to advantage in Figure 3. These sieves may be supported in any suitable 85 manner and as shown in Figure 3 the transverse division wall 13 of each tank is slightly spaced at its upper end with respect to the associated screen 38 and thereby to provide communication between the Hutch compartments of each tank. 90

For the middle or center sieve 38 there is provided a launder 39, and said launder having associated therewith a suitable baffle plate, whereby to divide the material passing therethrough and upon the screen 38, as illustrated in Figure 3. The screen 38 has also associated therewith a pair of aprons 40, one at each end thereof, and each apron communicating in turn with a launder 41 disposed centrally of the associated end screen 38. Each launder 41 is also provided with a suitable baffle plate, whereby the material passing therethrough will be divided previous to being deposited upon the associated screen 38. 100

It will be observed that each apron 40 has its inner end slightly elevated with respect to the middle or central screen 38, and the portion 42 of each end wall 12 of this tank is provided with a lining 42' upon its inner side and this lining is formed with a plurality of openings 43, preferably of the shape shown in Figure 6. Each opening 43 communicates with a similar opening 43' in the wall portion 42. Each wall portion 43 has associated therewith a gate 44 which is slideable upon the inner side of the lining 42' of said wall portion and which is provided with a plurality of notches 45, along its lower edge. Each member 44 is also provided with an inwardly extending flange 46, whereby the gate 44 is suspended through means of bolts 47, brackets 47' and springs 48. Also suitable nuts 49 are carried by the bolts 47, whereby the position of the associate gate may be adjusted. The openings 43 each are adapted to deposit material flowing therethrough into a trough 50, and said troughs may communicate with any suitable 115 120 125 130

receptacle. As shown in Figure 3 similar troughs 52' are provided for the end screens 38 and also similar gates 44' for controlling the flow of material into these troughs. Furthermore, each end screen 38 is provided with a pair of discharge aprons, one at each end thereof, as at 53, which are adapted to deposit material in suitable troughs 54 which communicate with a dewatering tank 55 in 10 each instance.

The operation of the present jig is similar in many ways to the operation of jigs now in use. The material for treatment passes from the feed laundry 39 upon the screen 38 midway between the ends of said screen and said material flows in opposite directions. The heavy or valuable minerals pass over the sieve 38 and settle down along the sieve and if sufficiently small pass through the interstices of the ore bed and screen into the hopper or hutch below, from which they are removed through faucets connected with the openings 20. The larger and heavier particles of the minerals settle down near the 25 sieve and are removed by means of the ore gates 44; the valuables being received by the troughs 50 and disposed of as desired. The lighter and remaining portions of the gangue matters and middling products pass over the discharge ends of the central sieve and upon the end sieves where reconcentration is affected. The beds of minerals upon the 30 end screens 38 should be thinner than beds on central screen and the minerals of somewhat lower specific gravities in order to effect the free settling conditions which are highly essential for the efficient concentration of low gravity materials. Of course, the process of concentration on these last-named sieves is the same as that of the central sieve excepting the middling products are removed from the end sieves instead of free ore products as with the central sieve and the overflow products or tailings 35 passing over the aprons 53 and conveyed by the troughs 54 into the dewatering tanks 55 and then disposed of as usual. Of course, it is to be understood that water is supplied to the different hutch compartments and that the plungers are operated in 40 order to carry out this operation.

In the jig heretofore described, it will be observed that the original mineral feed is received in only one place, while the overflow products are disposed in four places, thereby providing for a less decline of flow lines, a lower velocity of overflow waters, and a more equal thickness of ore-beds, without reducing the amount of work performed, 45 and enabling the jigs to be operated with the sieves in a truly level position. By this arrangement of the sieve compartments it will be practicable to employ beds of minerals of almost equal thickness, and thereby providing for unequal and unrestricted settling

conditions throughout the entire length of the sieves and higher ore recoveries.

Furthermore, in the jig of my invention heretofore described, the sieve compartments and flow lines are so arranged that the velocity of overflow waters and minerals decreases between the points of feed entry and overflow. By such arrangement the velocity of the overflow waters and minerals will be greatly reduced when compared to jigs of the tandem type having equal sieve areas and treating an equal tonnage or equal amount of minerals. By this improvement in jigs the following advantages are obtained: first, the collection of considerable quantities of fine materials resulting from a much lower velocity of overflow waters and better settling conditions; second: the collection of coarser materials and middling products of comparatively low gravities due to the decreased agitation of the surface of mineral beds and also due to the low velocity of such minerals.

Also it should be noted that in the jig of my invention the sieves and flow lines are so arranged that the efficiency of the several sieve compartments increases toward the points of overflow, and the higher gravity materials are extracted on the central and less efficient sieve, but where differences in gravities are usually ample for efficient concentration. The lower gravity materials and middling products are extracted on the end or secondary sieves which are most efficient in operation, thereby providing for higher jigging efficiency and enabling a higher degree of extraction of the more refractory mineral products.

Also by using the longer sieves as in the present invention and arranging the flow of the material as shown and described, that is, depositing the material midway of the sieve and then permitting the same to divide and flow in opposite directions much more time is allowed for the concentration of low gravity materials and middling products while passing over a sieve.

It will also be observed that with the improved form or ore and middling gates that the coarser and higher gravity ores may escape, said ores stratifying near the bottom of the beds. These gates operate due to the agitation caused by the plungers and will rise upon each surge of the water beneath the sieves caused by the action of the plungers and thereby permit the ores referred to to escape through the openings 43 into the troughs 40. These gates, of course, close at other times and prevent the escape of finer and lower gravity gangue matters which stratify near the top of the beds. These finer particles will, of course, eventually pass over the aprons 40 of the middle sieve and over the aprons 43 of the end sieves. In substance, by providing the ore

gates of my invention, the following advantages are obtained: First, the sieve concentrates are drawn in a straight line, with the direction of flow thereof; second, the concentrates are drawn the entire width and at both ends of each sieve; third, the uniform thickness of ore beds is maintained, and fourth, the removal of the sieve concentrates is made easier and also provides for cleaner 10 sieve concentrates to be obtained.

Referring to Figures 8 and 9 in which I have shown a modification of the present invention, the device may be described as having two tanks 60 and 61. The tank 60 is 15 of a greater length than the tank 61 and in one side of this tank there is formed a plurality of plunger compartments 62 in the same manner as described for Figures 1 to 7, inclusive. The tank 60 is also provided 20 with a longitudinally extending division wall 63, whereby to provide the hutch compartments or hoppers in the forward end of the tank and which communicate with the plunger compartments in the same manner 25 as that described for the jigs shown in Figures 1 to 7, inclusive. In the compartments forward to the division wall 63 there is arranged a plurality of screens 64 which are in tandem relation and also inclined, so 30 that material fed into the hopper 65 will gravitate downward upon these screens. In each of the plunger compartments there is arranged a plunger and which is suitably connected through the connecting rod, as 35 shown in Figure 10, to a shaft 65, said shaft carrying eccentrics adapted to reciprocate these plungers. The shaft 65 may be driven from a belt pulley 66. The tank 61 is provided with two plunger compartments 67 and 40 in each compartment there is provided a plunger 68 which is driven from a shaft 69, said shaft being also provided with a drive pulley 70. The plungers 68 are connected to the shaft 69 so that the same will be reciprocated. Also the tank 61 is provided with a longitudinal divisional wall 71, whereby to 45 provide different screen compartments or hatches in the forward end portion of the tank and in which there is positioned an elongated screen 72.

An apron 75 is adapted to deliver the material from the lowermost screen 64 to the middle of screen 72, and at this point the material will be divided and then move in 55 opposite directions upon the screen 70. The screen 70 is equipped with ore gates of the type heretofore described, and these ore gates discharge through suitable openings in the end walls of the tank into troughs 76. 60 Also suitable troughs 77 are provided to collect the gangue and other material which pass over the top of the ends of the tank and these materials are brought into a dewatering tank 78. The last-described portion of 65 this jig comprises a unit similar to either

one of the units shown in Figure 1, and operates in the same manner. By providing a jig of this character it is obvious that different ore may be operated upon, that is, the sieves arranged in tandem may be utilized to 70 first stratify the material and then this material after being subjected to this sieving operation may be lastly subjected to the sieve operation in which the material is guided and passed over a longer screen. It 75 has been found that with a jig of this construction the same is adapted to work upon most any material and also may be used to an advantage for primary and finishing jig services. 80

The jig previously described and shown in Figures 1 to 7, inclusive, is particularly adapted for extracting the lower gravity materials and middling products as well as 85 the very fine ores.

While I have shown and described two specific forms of my invention I wish it to be understood that I am aware of the fact that changes in the general arrangement and combination of parts may be made by 90 those skilled in the art without departing from the spirit of my invention, as indicated by the appended claims.

I claim:

1. In an ore jig of the character described, a sieve compartment having a wall provided with a plurality of aligned openings, a gate comprising a plate member having notches in its lower edge and adapted to be arranged in registration with the openings in said wall, means for suspending the gate to permit upward movement thereof, and a flange extending inwardly from said plate member adapted to serve as a baffle plate and cause an upward surge of liquid within the 100 associated sieve compartment to move the gate member upwardly and thereby increase the openings through the walls of said sieve compartment. 105

2. An ore jig of the character described, comprising a central sieve compartment, means for delivering material to be separated upon the central portion of the sieve of said central compartment, a sieve compartment upon each side of the central compartment, and an inclined apron extending between the central portion of each side sieve compartment and the associated end of the central sieve compartment. 110

3. An ore jig of the character described, comprising a central sieve compartment, means for delivering material to be separated upon the central portion of the sieve of said central compartment, a sieve compartment upon each side of the central compartment, an inclined apron extending between the central portion of each side sieve compartment and the associated end of the central sieve compartment, and means whereby the material being deposited upon each of 115 120 125 130

said sieves may be divided, thereby to enable the material deposited upon each sieve to flow in opposite directions.

4. An ore jig of the character described, comprising a central sieve compartment, means for delivering material to be separated upon the central portion of the sieve of said central compartment, a sieve compartment upon each side of the central compartment, 10 an inclined apron extending between the central portion of each side sieve compartment and the associated end of the central sieve compartment, and there being gate controlled openings in the end walls of each sieve compartment, whereby to permit the discharge 15 of material having high specific gravity.

5. In an ore jig of the character described, a plurality of inclined sieves arranged in tandem relation, means whereby material may be delivered to the uppermost sieve, a horizontal sieve arranged forward to the lowermost inclined sieve, and means whereby material moving from the lowermost of the inclined sieves may be delivered upon the 25 horizontal sieve at a central portion thereof.

6. In an ore jig of the character described, a plurality of inclined sieves arranged in tandem relation, means whereby material may be delivered to the uppermost sieve, a horizontal sieve arranged forward to the lowermost inclined sieve, means whereby material moving from the lowermost of the inclined sieves may be delivered upon the 30 horizontal sieve at a central portion thereof,

and means whereby the material delivered 35 to said horizontal sieve may be divided before being deposited upon said sieve.

7. In an ore jig of the character described, a plurality of inclined sieves arranged in tandem relation, means whereby material 40 may be delivered to the uppermost sieve, a horizontal sieve arranged forward to the lowermost inclined sieve, means whereby material moving from the lowermost of the inclined sieves may be delivered upon the 45 horizontal sieve at a central portion thereof, a wall for each end of the horizontal sieve, and gate-controlled openings in each wall whereby to permit the discharge of materials 50 having high specific gravities.

8. In an ore jig of the character described, a plurality of inclined sieves arranged in tandem relation, means whereby material may be delivered to the uppermost sieve, a horizontal sieve arranged forward to the 55 lowermost inclined sieve, means whereby material moving from the lowermost of the inclined sieves may be delivered upon the horizontal sieve at a central portion thereof, a wall for each end of the horizontal sieve, 60 gate-controlled openings in each wall, whereby to permit the discharge of materials having high specific gravities, and an apron disposed above each end wall of said horizontal sieves and adapted to discharge materials having a low specific gravity.

ELMO M. DAUGHERTY.
